UNITED STATES PATENT OFFICE.

OSCAR TREIER, OF BROOKLYN, NEW YORK.

ENGINE VALVE MECHANISM.

1,063,477.

Specification of Letters Patent.

Patented June 3, 1913.

Original application filed March 23, 1912, Serial No. 685,866. Divided and this application filed August 10, 1912. Serial No. 714,327.

To all whom it may concern:

Be it known that I, OSCAR TREIER, citizen of the Republic of Switzerland, residing at Brooklyn, in the county of Kings and 5 State of New York, have invented certain new and useful Improvements in Engine Valve Mechanisms, of which the following is a specification.

The present invention relates to valves 10 and has for its object to provide a new and improved mechanism more especially designed for use in internal combustion engines and arranged to insure proper opening and closing of the admission and 15 exhaust valves.

This application is a division from the application Serial No. 685,866, filed March 23, 1912.

A practical embodiment of my invention 20 is represented in the accompanying drawing forming a part of this specification and in which similar reference letters indicate corresponding parts, Figure 1 being a section on line 1—1 of Fig. 2 and Fig. 2 a sectional 25 top plan view of the engine.

With reference to the drawing, each of the engine cylinders A⁴ has a single passage A⁵ which serves both for the admission and exhaust of the fuel. The tubular valve 1 is slidably mounted in the tubular chamber A⁶ which extends transversely to the said 30 passage and to the said cylinders. This valve has a closed inner end 2 and an open outer end 2' and divides the chamber A⁶ 35 into two compartments of which the left hand compartment leads into the exhaust pipe A¹⁰ communicating with the exhaust opening of the chamber A⁶, while the right hand compartment is formed within the in- 40 terior of the tubular valve 1 and communicates with the supply pipe A⁹ which leads into the admission opening of the chamber A⁶. The tubular valve bears on the inner surface of the chamber A⁶ by means of 45 suitable packing rings 3 and is provided with circumferential openings 4. Within the valve body a spiral nozzle 5 is provided which projects toward and terminates near the inner closed end 2 of the valve. This 50 nozzle has its main object to cause a thorough mixture of the liquid gasoline with the air and another object to decrease the tension of the fuel prior to its entering the cylinder. A further result of the nozzle is

that when the mixture comes in contact with 55 the heated opposite wall of the valve, the gasoline will be caused to evaporate while the air will cool the valve.

Various means may be employed for operating the hollow valves, as for instance 60 those shown in the drawing and particularly as described in the application above referred to.

It will be seen that when the valve occupies the position shown in Fig. 1 the passage 65 A⁵ of the cylinder will be opened and the burnt fuel from the cylinder will be permitted to exhaust through the said passage and the circumferential openings A⁸ of the chamber A⁶ into the exhaust pipe A¹⁰. On 70 the other hand, when the valve body 1 moves to the left it will close the openings A⁸ of the chamber A⁶ and establish communication between its own openings 4 and the passage A⁵ of the cylinder A⁴, so that fresh fuel entering the interior of the valve 1 and flowing through the spiral nozzle 5 will be admitted into the cylinder A⁴. 75

What I claim and desire to secure by Letters Patent is:

1. In a valve mechanism for engines the combination with the engine cylinder having an admission and outlet passage, of a tubular valve chamber, having an admission opening at one end, an exhaust opening at 85 the other and circumferential openings in alinement with the said passage, a tubular valve body slidably mounted in said chamber and having circumferential openings, the inner end of said valve body being tightly 90 closed and the outer end thereof being open, a nozzle in the interior of said tubular valve directed toward the said closed end of the latter, said valve being adapted to alternately establish communication between the 95 said cylinder and the said chamber to permit the fuel to exhaust, and between its interior and the said cylinder to admit fresh fuel.

2. In a valve mechanism for engines, the combination with an engine cylinder having a passage for the admission and exhaust of fuel, of a tubular valve chamber having an admission opening at one end, an exhaust opening at its opposite end and circumferential openings in alinement with the said passage, a tubular valve body slidably mounted in said chamber and having cir- 105

cumferential openings, the inner end of said valve being tightly closed and the outer end thereof open, and a spiral nozzle in the interior of said tubular valve directed toward 5 the said closed end of the latter, said valve being adapted to alternately establish communication between the said passage and the said chamber to permit the fuel to exhaust,

and between its interior, and the said cylinder to admit the fuel.

In testimony whereof I affix my signature in presence of two witnesses.

OSCAR TREIER.
